UNITED STATES PATENT OFFICE.

ADAM J. EISMAN, OF BUFFALO, NEW YORK.

DOOR-CHECK.

1,398,010.

Specification of Letters Patent.

Patented Nov. 22, 1921.

Application filed December 4, 1919. Serial No. 342,378.

To all whom it may concern:

Be it known that I, ADAM J. EISMAN, a citizen of the United States, residing at Buffalo, in the county of Erie and State of New York, have invented certain new and useful Improvements in Door-Checks, of which the following is a specification.

This invention relates to combined door checks and retainers, and is designed to eliminate the slamming of a door and also to hold the door in open position when desired.

The object of my invention is the production of a device of this character, which is simple, inexpensive, and thoroughly efficient in the performance of its functions, and which may be either applied to a door jamb and have pivotal connection with the door or to a door and have pivotal connection with a jamb, as may be desired.

The invention consists in the novel features of construction, and in the arrangement and combination of parts to be hereinafter described and more particularly pointed out in the subjoined claims.

In the drawings:

Figure 1 is a side elevation of a wall showing a portion of a door opening and a door closing said opening with a portion of the door jamb and the door in section, and showing a longitudinal section of my improved door check and retainer in the manner it is applied to the jamb with a part thereof pivotally connected to the door.

Fig. 2 is a horizontal section taken through the door jamb and through the device applied thereto, on line 2—2, Fig. 1, the jamb being broken away at two points to show parts of the door beneath.

Fig. 3 is an enlarged transverse section taken on line 3—3, Fig. 1.

Fig. 4 is a sectional perspective view of the device with parts thereof separated but in operative relation to each other, and with a part of the device pivotally connected to a door.

Referring now to the drawings in detail, the reference numeral 5 designates a wall of a building having a door opening 6 therein, a door frame including a door jamb 7, and a door 8 hinged to one of the sides of the door frame, as at 9.

My improved door check and retainer is herein shown as applied to the header jamb of the door, and to permit of this, said jamb is formed with a longitudinal recess or de-

pression 10, to opposite end walls of which gripping springs 11, 12 are secured, each of which has two spaced spring members 13 which gradually approach each other at one end and have the ends flared outwardly, as at 14.

Arranged within the depression 10 between said springs is a metallic guide 15 which snugly fits said depression and is fastened to the horizontal jamb 7 by screws, or otherwise. This guide is formed of a strip of sheet metal bent into substantially rectangular form in cross section with a slot 16 in its bottom wall and therefore comprises 70 a top wall 17, side walls 18, and two inwardly-extending or opposed flanges 19 spaced apart to form the slotted bottom wall. This guide is therefore hollow and open at opposite ends with the slot 16 extending from end to end thereof.

Slidable within the guide 15 is a check and retainer member 20, said member having an intermediate portion of cross sectional shape to correspond to the interior of said 80 guide so that it is in physical contact with all the walls of said guide.

At opposite ends, said check or retainer member 20, which may be termed a slide, is reduced in thickness and formed with a 85 concaved portion 21 and a convex portion 22 at both the top and bottom of each reduced portion with the outer ends of the slide rounded, as at 23. This slide has pivotal connection, as at 24, with one end of a link 90 or bar 25, the opposite end of which latter is pivotally connected to the upper edge of the door 8, as at 26.

With the door hinge at the right of an opening, the slide 20 is at the extreme left 95 of its movement when the door is closed and the left hand end of said slide is retained between the spring members of the gripping spring 11, which spring may be termed a check spring. When the door is swung open 100 to the position indicated by dotted lines in Fig. 2, the slide will have been moved within the guide 15 to its extreme right position, as indicated by dotted lines in Fig. 1, with the right hand end of the slide forced between 105 the spring members of the gripping spring 12, which spring may be termed a retainer spring.

It is therefore apparent that upon opening the door, the slide 20 is moved from left 110 to right within the guide 15, and when closing the door it is moved from right to left

within said guide. When, however, a door is hinged at the left of an opening, reverse action of the slide takes place, assuming the door is swung to the same side of the wall, 5 and in such case the gripping spring 11 becomes the retainer spring while the gripping spring 12 becomes the check spring.

With the door closed, the link or bar 25 is positioned directly underneath the guide, 10 as best shown in Fig. 3, and one edge thereof lies against one of two depending lips 27 arranged on one of the flanges 19 forming the slotted bottom wall of the guide, each 15 of said lips being formed by cutting incisions in the flange and bending the metal between said incisions downwardly, as best shown in Fig. 4. Therefore, with my invention it will be found unnecessary to employ the usual door stops except of course 20 on exterior doors where door stops are always needed.

During the act of opening the door, the slide is moved within its guide toward the hinged edge of the door and finally has that 25 end of the slide close to the hinged edge of the door engaged by the spring members of the retainer spring 12, which spring members are forced apart until the convex portions of said slide end pass beyond the extremities of the spring, as shown by dotted lines in Fig. 1. When the slide is in this 30 position the door is opened to its limit and will be retained in this position so that air drafts passing through a room cannot close 35 the door, and it is necessary to exert sufficient pressure on the door in the direction of its closing movement to disengage the slide from the retainer spring before the door can be closed. When the door reaches the 40 end of its closing movement, the opposite end of the slide engages the check spring 11, causing the spring members thereof to separate until the convex portions of said slide end pass the extremities of said spring 45 members. The spring members of the check spring therefore prevent slamming of the door and necessitate the use of some pressure, or require momentum in the movement of the door in order to completely close the 50 latter.

It is apparent that either of the springs may be dispensed with and one end of the slide only be formed as shown; in which case, if the retainer spring only is used the 55 device will serve as a door retainer only, while if the check spring only is used, the device will serve as a door check only to prevent slamming of the door when closed by air drafts.

It is also apparent that the slide and its 60 coöperating parts may be fitted into the upper edge of the door, with the link or bar 25 pivotally connected to the door jamb. In the event of this device being used on a 65 double door; that is, one swinging to op-

posite sides of the wall, the stop lips 27 on the guide 15 may be dispensed with. It is also to be noted, viewing the wall as shown in Fig. 1, that if the door were hinged at the left hand end, it would be necessary to 70 change the pivotal point 26 of the bar or link 25, and if the door were to be swung to the opposite side of the wall and the stop lips were to be utilized in conjunction with the bar or link 25, it would be necessary 75 to reverse the guide in order to bring the stop lips to the opposite side of the slot 16 within said guide.

Having thus described my invention, what 80 I claim is:—

1. The combination with a wall having a door opening provided with a longitudinal depression in the header jamb thereof, and a door for closing said opening, of gripping springs at opposite ends of said depression, a slide movable within said depression between said gripping springs, and a link pivotally connected at one end to said slide and at its other end to the upper edge 90 of said door.

2. The combination with a wall having a door opening provided with a longitudinal depression in the header jamb thereof, and a door for said opening, of gripping springs at opposite ends of said depression, a slide 95 member movable between said gripping springs and adapted to engage said springs as the door approaches the ends of its movements in opposite directions, and a link pivotally connecting said door with said 100 slide to cause movement of the latter when moving the door.

3. The combination with a wall having a door opening provided with a longitudinal depression in the header jamb thereof, and a 105 door for said opening, of springs at opposite ends of said depression, a slide member within said depression adapted to have each end thereof engage one of said springs, and connection between said slide and said 110 door to cause said slide to move toward or from either of said springs.

4. The combination with a wall having a door opening provided with a longitudinal depression in its header jamb, and a door 115 hinged to said opening, of a spring at one end of said depression, a slide member within said depression adapted to engage said spring, and a link having opposite ends pivotally connected to said slide and door, 120 respectively.

5. The combination with a wall having a door opening provided with a longitudinal depression in its header jamb, and a door 125 hinged to said wall to open or close said door opening, of a hollow elongated guide fitted in said depression, a slide movable in said guide, means in said depression to engage one end of said slide and retain said slide when the door is in full open position, and 130

a link pivotally connected at one end to said slide and having pivotal connection at its other end with said door.

6. The combination with a wall having a door opening provided with a depression in its header jamb, and a door for said opening, of a guide fitted in said depression, a slide movable in said guide, yielding means at one end of said depression adapted to be engaged by one end of said slide when closing the door to prevent slamming thereof, and means for pivotally connecting said slide with said door to cause movement of said slide when moving said door.
- 15 7. The combination with a wall member and a door member hinged to said wall member, one of said members having a depression therein, of a slide reciprocable within said depression, a link having one end thereof pivotally connected to said slide and having pivotal connection at its other end with said other member, and a spring at one end of said depression adapted to be engaged by said slide to check the closing movement of the door and prevent slamming thereof.

8. The combination with a wall member and a door member hinged to said wall member, one of said members having a depression therein, of a slide reciprocable within said depression, a link having one end thereof pivotally connected to said slide and having pivotal connection at its other end with said other member, and a spring at one end of said depression adapted to be engaged by said slide to retain the door in full open position.

9. The combination with a wall member and a door member hinged to said wall member, one of said members having a longitudinal depression therein, of a slide reciprocable within said depression, a link having one end thereof pivotally connected to said slide and having pivotal connection at its other end with said other member, and springs at opposite ends of said depression adapted to be engaged respectively by opposite ends of said slide when opening said door member to its full extent and when closing said door member.

50 10. The combination with a wall member having a door opening, and a door member hinged to said wall member for closing said

door opening, one of said members having a longitudinal depression therein, of a hollow guide fitting within said depression and having opposite ends open and a slot in one of its walls extending from end to end thereof, a slide fitting within said guide and having reduced ends provided with concave and convex surface portions, a gripping spring at each end of said depression adapted for engagement with the concave and convex surface portions at corresponding ends of said slide, and a link pivotally connected at one end to one of said members and having pivotal connection at its opposite end to said slide, the pivot at said opposite end extending through the slot of said guide.

11. The combination with a wall member having a door opening, and a door member hinged to said wall member and adapted to close said door opening, one of said members having a longitudinal depression therein, of a hollow guide fitted in said depression and terminating short of the ends thereof, said guide having a longitudinal slot through one of its walls and a stop lip extending from said wall, gripping springs at opposite ends of said depression, a slide reciprocable within said guide and having opposite ends shaped to conform to said gripping springs to be gripped thereby, and a link pivotally connected at one end to one of said members and having its other end pivotally connected to said slide, the pivot at said other end passing through the slot of said guide.

12. The combination with a wall member having a door opening and a door hinged to said wall member adapted to close said opening, of a reciprocable element on one of said members having one end provided at opposite sides with concave and convex surface portions, a link pivotally connected at one end to the other member and having its other end pivotally connected to said reciprocable element, and a spring having two spaced spring members gradually approaching each other at one end and adapted to receive the concave and convex surface portions of said reciprocable member.

In testimony whereof I affix my signature.

ADAM J. EISMAN.
